WINDOW

William D. Bayley, Springfield, Ohio

Application September 15, 1937, Serial No. 163,984

20 Claims. (Cl. 189—64)

This invention relates to windows and more particularly to a closure assembly for a ventilating area.

An object of this invention is to provide a closure adaptable for field assembly.

Another object of this invention is to provide a closure assembly that may be attached to the fixed portion of the window in any selected location without alterations.

10 Another object of this invention is to provide a window assembly that is cheap, efficient, easily manufactured and readily assembled, but at the same time dependable and durable.

Another object of this invention is to provide 15 an interlocking arrangement between the frame bounding the ventilating area and the closure frame.

Another object of this invention is to provide 20 an interlocking arrangement between the sill extending along the bottom of the ventilating area and the closure frame.

Another object of this invention is to provide 25 weather tightness of a field closure assembly against the fixed frame portion.

25 Other objects and advantages reside in the construction of parts, the combination thereof and the mode of operation, as will become more apparent from the following description.

In the drawings, Fig. 1 discloses a cross sectional view of the window and the closure assembly 30 for the ventilating area.

Fig. 2 is a partially exploded view of the closure assembly in readiness to be inserted in position upon the fixed portion of the window, which 35 portion is shown in section.

Fig. 3 is a sectional view taken substantially on the line 3—3 of Fig. 1.

Fig. 4 is a sectional view of a modification.

Fig. 5 is a fragmentary cross sectional view of 40 another modification.

Fig. 6 is a perspective view of a closure retaining member.

Fig. 3 has been oriented through an angle of 45 90°, as it was not convenient to show this figure transversely across the sheet of drawings.

In the past it has been the common practice when erecting a building using metallic windows to glaze the window after the completion of the 50 outside walls. This proves advantageous in that the hazard of breaking the window panes when erecting the walls is eliminated. The glazing however, proves to be a very expensive operation when it is done after the erection of the outside walls. Up to the present time no other method

has been developed, as far as known, of glazing the fixed portions of the window.

In duo-functional windows used in penal institutions, that is, where the muntin bars of the window function as glass supporting bars and as 5 detention bars, the closure for the ventilating area may be assembled at the factory or on the grounds and after assembly mounted in position over the ventilating area with the glass panes already in position. Likewise, the closure for 10 standard commercial windows may be glazed at the factory, at some central point or on the job before mounting. This will hereinafter be referred to as "field assembly." In field assembly windows, when the frame for the closure overlying 15 the ventilating area is shipped from the factory without window panes, the glass is inserted when the closures are on the ground. This permits of progressive operations by the employees. One mechanic, for example, may position the 20 frames on suitable racks. A succeeding mechanic may lay the glass panes in position; a third may putty along one or more sides, there being as many mechanics as separate operations, in the event the job is large enough. This has been 25 found to greatly reduce the cost of the window assembly.

After the closure frames have been glazed, the closure assembly is raised and placed in position over the ventilating area. This permits the use 30 of a ventilating area in any selected place in the window. Any space or group of spaces left vacant for ventilation may be provided with a closure. It is not necessary that all of the windows be 35 uniform.

Referring to the drawings, the window assembly 35 includes a plurality of horizontal muntin bars 10 and a plurality of transversely disposed vertical muntin bars 12 dividing the window into a plurality of spaces, some of which are glazed by window panes 14, leaving a plurality of spaces 40 vacant for ventilating area. The muntin bars 10 and 12 may extend across the ventilating area to function as detention bars, or security bars, as the case may be.

45 In the modification disclosed, both the vertical and horizontal muntin bars constitute T-bars, having the flanges on the inside. Thus, the putty 16 used in putting the window panes of the fixed spaces is located on the outside of the window, so 50 as to be out of reach of the inmates.

It is very desirable to make a field assembly of the closure unit overlying the ventilating area. By assembling the closure unit on the ground the cost of production is greatly reduced. In 55

the embodiment best seen in Figs. 1, 2 and 3, the closure unit includes a fixed frame portion including a sill 20 and horizontal and vertical frame members 22. As may best be seen by referring to Figs. 2 and 3, the overhanging portion 24 of the sill is provided with one or more notches 26, one notch for each vertical muntin bar passing through the ventilating area. The overhanging portion provides drainage for water. The sill 20 carries a flexible or rigid retaining member 28, as the case may be, welded or otherwise secured to the under side of the sill 20. The flexible member 28 is provided with an angularly disposed portion 28a projecting towards the downwardly projecting sill portion 24. The angularly disposed portion 28a merges into a second deflected portion 28b. Portions 28a and 28b cooperate with the overhanging lip portion 24 to form a channel 30, adapted to slip over the upwardly projecting flange 32 of the muntin bar 10 bounding the bottom of the ventilating area. In order to provide weather tightness a suitable mastic 34, or packing material, surrounds the upper flange 32 and fills the channel 30.

25 The frame portion 22 is provided with a notch 36 supporting a sheet metal member 38 having a channel portion 40 adjacent to the flanges bounding three sides of the ventilating area. The channel 40 is also filled with a mastic, or any other suitable pliable or yieldable material adjusting itself to the contour of the contacting surfaces, so as to seal the edges of the ventilating area.

35 The muntin bars extending across the ventilating area function as detention bars in preventing the ingress and egress of human bodies through the window. In order to prevent the passing of small bodies, such as tools, implements, guns and the like, and in order to provide protection against 40 insects, a screen 44 overlies the ventilating area. The frame 42 of the screen 44 is seated against the inwardly projecting portion of a sheet metal member 38. In addition thereto, the screen functions as a tell-tale, in that if it is mutilated 45 or removed, it serves as a signal that an attempt at escaping through the ventilating area is about to be made or an escape has been made.

50 After the closure assembly has the channel 30 hooked over and interlocked with the upwardly extending flange 32, the closure assembly is bolted in position by a plurality of bolts or screws 50 passing through a washer 52 seated upon a retaining member 54, preferably provided with an arcuate portion overlying an arcuate flange 55 overlying a corner formed between the vertical and horizontal muntin bars. The flange 55 of the retaining member 54 is preferably provided with lugs 56, best seen in Fig. 6. Lugs 56 are adapted to abut the frame of the closure to hold 60 the parts in a more rigid relation to each other.

65 The screw 50 threadedly engages a suitable aperture 60 in a nut carried by the fixed closure frame 22. The head of the screw 50 is preferably made for use with a special tool, which prevents the removal of the screw 50 with an ordinary wrench or the like. By tightening the screws 50 the frame 22 is securely held against the fixed muntin bars bounding the ventilating area. The mastic or sealing material 34 and the 70 mastic or sealing material in the channel 40 seals the boundary of the ventilating area. This permits the entire closure assembly being assembled on the ground floor or any other suitable place, where it is glazed before being placed on the 75 fixed window portion. The retaining member 54

eliminates the use of holes being made in the muntin bar. Furthermore, it eliminates the use of lugs for holding the closure in position.

By this arrangement it is possible to leave any selected group of spaces vacant for a ventilating area. After it has been decided upon what spaces are to be left vacant and the number of spaces, a suitable closure assembly may then be inserted, irrespective of the position of the spaces, without any alteration of the fixed window portion. These spaces may be in the top of one window, in the bottom of another, or any intermediate location. Likewise, a few spaces may be left vacant, or a great number of spaces may be left vacant. This arrangement permits a very flexible selection of ventilating area, both as to size and location, thereby permitting the production of standard parts at the factory, the standard parts being inserted in the field, thus resulting in the reduction of the cost of production. 20

Furthermore, the screws 50 permit the removal of the closure assembly. Thereby this structure has flexibility, in that it is merely necessary to remove the screws 50 to move it to any other suitable location. In the event the ventilating areas have been improperly located or it is necessary to meet changed conditions, the ventilating area may be shifted to another portion of the same window by merely removing the necessary glazing, transferring the closure assembly to the new ventilating area and glazing the unused old ventilating area. Additional ventilating areas may be provided by removing glazing from desirable glazed spaces and adding another closure assembly. Either shifting the old or adding new closure assemblies does not in any manner mar the appearance of the window assembly, as no holes, notches or recesses are required in the muntin bars and no parts are welded thereto. 30

35 The sill 20 and the frame 22 cooperate to support a pivotally mounted closure assembly including a sill portion 70, transversely disposed muntin bars 72 and horizontal and vertical members 74, cooperating to support the glazing 76. Again, the putty is placed on the outside of the closure so as to be out of easy reach of the inmates. The transversely disposed muntin bars 72 extending across the closure frame are of less width or thickness than the sill 70 and the frame member 74, so as to provide a pocket for the 40 screen 42. The sill 70 is provided with a downwardly projecting flange 78 contacting a slanting surface of the sill 20. In addition to the downwardly projecting flange 78, the sill 70 has another downwardly projecting flange 80 engaging 45 the inside of a downwardly projecting portion of the sill 20, so as to provide a double contact arrangement, providing a dead air space 82 between the double contacts. The flange 78 terminates in 50 spaced relation with respect to the bottom of the screen frame 42. Members 74 are provided with a pair of outwardly projecting flanges 90 and 92. These form a double contact with the frame member 22 leaving a dead air space 94. The flange 92 subtends or overlies the screen frame 42. 55

60 In the modification disclosed in Fig. 4, a sill 100 has been used. This sill is made from a piece of material bent into a loop, so as to provide a cavity 102 in the bottom thereof, forming a receptacle into which the inrushing weather is 65 trapped, without blowing into the juncture formed with the downwardly projecting flanges 78 and 80 of the sill of the movable closure. By 70 properly designing this sill, a structure may be obtained wherein there will be no tendency for 75

the weather to escape through the juncture between the movable closure and the fixed sill portion. This structure is very effective as a safeguard against blowing rain.

5 In this modification the sill 100 supports a flexible member 104 cooperating with the downwardly projecting flange 106 to form a channel 108 into which the flange 32 projects. The sill 100 supports a pair of vertically disposed frame members 110 and a transverse top member 112. Members 110 and 112 are provided with inwardly projecting flanges 114 providing an abutment for the frame members 116 of the movably mounted closure. A sheet metal member 115 is mounted between the inwardly projecting flange 114 of members 110 and 112, and the flanges of the T-shaped muntin bars 10 and 12. The sheet metal member 115 terminates in a channel 118 extending beyond the frame members 110 and 112 for supporting sealing material 120 contacting the outer edges or inner edges, as the case may be, of the flanges of the muntin bars bounding the fixed portion of the window. The sealing material 120 may be some initially plastic material or some yieldable material, such as felt.

The closure assembly is held in position by the screws or bolts 59, holding the clamping member 54 against the flange of the muntin bar bounding the ventilating area and engaging a suitable nut on the opposite side of the inwardly projecting flange 114, in a manner similar to that disclosed in connection with the preferred embodiment shown in Fig. 1.

In the modification disclosed by the fragmentary view shown in Fig. 5, the fixed frame portion of the window includes an irregular shaped bar 130 bounding the ventilating area and having attached thereto a closure assembly including the frame member 134 and the metallic member 132 extending in parallel relation thereto. Suitable bolts 135 hold members 132 and 134 in spaced relation to form the channel 138. The frame member 134 is provided with an inwardly projecting flange 136. Instead of utilizing a sheet metal member 38 or 115 for holding the sealing material, as disclosed in Figs. 1 to 4, the sealing material is packed into the channel 138 formed between members 132 and 134. The movably mounted closure, including the frame 140, is provided with an outwardly projecting flange portion 142 contacting the edges of the flange portion 132 and the frame portion 134.

Although the preferred modification of the device has been described, it will be understood that within the purview of this invention various changes may be made in the form, details, proportion and arrangement of parts which generally stated consist in a device capable of carrying out the objects set forth, in the novel parts, combination of parts and mode of operation, as disclosed and defined in the appended claims.

Having thus described my invention, I claim:

1. In a window having a plurality of transversely disposed muntin bars dividing the window into a plurality of spaces some of which are glazed leaving at least one space vacant as a ventilating area bounded by the muntin bars forming a frame, a closure assembly adapted to be mounted in position upon the frame bounding the ventilating area, said closure assembly including a stationary frame having a sill overlapping the frame portion extending along the bottom of the ventilating area, and a metallic flexible member carried by said sill and coop-

erating therewith to clamp the side of the frame portion extending along the bottom of the ventilating area to seal the juncture between the sill and the frame portion bounding the ventilating area.

2. In a window having a frame bounding a ventilating area, said frame having an upwardly projecting portion extending along the bottom of the ventilating area, a closure assembly for the ventilating area, said closure assembly including a stationary frame having a downwardly projecting channel seated on the upwardly projecting portion of the frame bounding the ventilating area so as to hold one side of the stationary frame in fixed spaced relation with respect to the frame bounding the ventilating area, one wall of the channel being formed from a flexible material adapted to cooperate with another wall of the channel to clamp a portion of the frame bounding the ventilating area so as to clamp and seal the juncture between the stationary frame and the frame bounding the ventilating area.

3. A window assembly including a plurality of transversely disposed muntin bars dividing the window into a plurality of spaces, some of which are glazed leaving a space vacant for ventilating area, a closure assembly for the ventilating area including a fixed metallic frame portion, a second frame movably supported upon the first frame, glazing carried by said second frame, said glazing being mounted in the frame in offset relation with respect to the plane formed by the extreme outer surfaces of the muntin bars so as to form a cavity between the glazing and the surfaces of the muntin bars, said movable closure frame having a portion projecting towards the muntin bars, said portion contacting a flange bounding the top of the ventilating area, said assembly including a downwardly projecting member having a channel, said member being disposed intermediate a portion of the fixed metallic frame and the muntin bar extending along the top of the ventilating area, said member projecting below the portion of the closure projecting towards the muntin bars.

4. A reentrant sill for use with a ventilator, a closure assembly movably mounted thereon for closing any selected group of spaces left vacant in a window having a plurality of transversely disposed muntin bars, said reentrant sill including a portion having a substantially U-shaped cross sectional area having the legs disposed in a generally horizontal direction, the lower leg being extended and provided with a downwardly projecting flange overlapping a portion of the muntin bar extending along the bottom of the window and a flexible member attached to the under side of the lower leg, said flexible member being provided with a downwardly projecting portion disposed in spaced relation from the flange and adapted to contact the muntin bar extending along the bottom of the window.

5. A reentrant sill for use with a ventilator having a closure assembly mounted therein for closing any selected group of spaces left vacant in a window having a plurality of transversely disposed muntin bars, the muntin bar across the bottom of the ventilating area having a flange portion projecting upwardly, said reentrant sill including a channel-shaped portion having the sides thereof substantially horizontally disposed and directed outwardly, the upper side of the channel supporting the movably mounted closure, the lower side of the channel extending beyond

- the outer margin of the upper side and provided with a downwardly projecting flange seated over a portion of the muntin bar extending along the bottom of the ventilating area, said flange co-
 5 operating with said flange portion to provide water drainage, the longitudinally extending opening of the channel forming a water receiving pocket for driving rain.
6. A sill for a closure for a ventilator adapted for insertion upon a horizontal muntin bar in any optionally selected position, said sill including a substantially U-shaped portion having the legs thereof disposed in a generally horizontal position, the upper leg terminating in a downwardly projecting flange, the lower leg being extended and provided with a downwardly projecting flange overlapping a portion of the muntin bar extending along the bottom of the ventilating area, the upper leg supporting a movably mounted closure.
- 10 7. A reentrant sill for use with a ventilator, a closure assembly mounted thereon for closing any selected group of spaces left vacant in a window having a plurality of transversely disposed muntin bars, said reentrant sill including a portion having a substantially U-shaped cross sectional area having the legs extending in a generally horizontal direction, the upper leg of which sill terminates in a downwardly projecting flange, the lower leg of which sill is extended and is provided with a downwardly projected flange and a flexible member secured to the under side of the lower leg, said flexible member having a downwardly projecting portion arranged in spaced relation from the downwardly projecting flange so as to form a channel for gripping and engaging a portion of the muntin bar extending along the bottom of the ventilating area.
- 15 8. Attaching means for securing a closure in juxtaposed relation with respect to T-shaped muntin bars bounding any selected group of spaces left vacant for a ventilating area, said closure being provided with a frame bounding the ventilating area, said attaching means including a plate member having two straight edges disposed at right angles to each other and adapted to fit over intersecting flanges of the transversely disposed T-shaped muntin bars so as to be positioned adjacent the intersecting webs of the T-shaped bars, and a flange extending in a direction normal to the plate member, said flange terminating at the edges of the flanges of the T-shaped bars so as to form an abutment engaging the closure frame.
- 20 9. Attaching means for securing a closure in juxtaposed relation with respect to T-shaped muntin bars bounding any selected group of spaces left vacant for a ventilating area, said closure being provided with a frame bounding the ventilating area, said attaching means including a plate member having two straight edges disposed at right angles to each other and adapted to fit over intersecting flanges of the transversely disposed T-shaped muntin bars so as to be positioned adjacent the intersecting webs of the T-shaped bars, and means projecting over the sides of the plate member beyond the flanges of the T-shaped bars, said means engaging the frame of the closure assembly to provide rigidity.
- 25 10. Attaching means for securing a closure in juxtaposed relation with respect to T-shaped muntin bars bounding any selected group of spaces left vacant for a ventilating area, said attaching means including a fan-shaped retaining member simulating a quadrant of a circular area,
- the straight edges of which are adapted to engage the webs of the muntin bars bounding the ventilating area, and a portion adjacent the edges overlapping the flanges of the T-shaped bars, means extending normal to at least a portion of the arcuate edge directed towards the stationary frame so as to engage the same, said fan-shaped retaining member having an aperture and a bolt passed through the aperture and secured to the frame of the closure assembly for holding the closure assembly in position.
11. A closure assembly for use with any selected group of spaces left vacant in a window having a plurality of horizontal and vertical muntin bars dividing the window into a plurality of spaces, the horizontally disposed bars being provided with at least an upwardly projecting flange, said closure assembly including a sill and a movably mounted closure adapted to contact the sill, said sill being notched for the vertical muntin bars extending across the ventilating area, the notched portion including substantially horizontal portions and downwardly projecting flange portions adapted to be positioned one side of the upwardly projecting flange of the muntin bar extending across the bottom of the ventilating area, and a continuously extending downwardly projecting flange portion adapted to engage the side of the upwardly projecting flange opposite the side engaged by the downwardly projecting flange portions so as to seat the sill snugly upon said flange.
- 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 jecting portion so as to seal the juncture between the frame bounding the ventilating area and the stationary portion of the closure assembly.

15. In a window having a frame bounding a 5 ventilating area, said frame having an upwardly projecting tapered flange portion extending along one side of the ventilating area, a closure assembly for the ventilating area, said closure assembly including a movably mounted closure mounted 10 upon a stationary portion, said closure including a channel provided with one side having a substantially V-shaped cross sectional area so as to restrict the channel in width, said channel having a wide mouth facilitating the insertion of the 15 stationary portion upon the tapered flange of the frame bounding the ventilating area, the tapered flange being wedged into the restriction of the channel, and sealing means for sealing the juncture between the stationary portion of the closure 20 assembly and the frame bounding the ventilating area to provide weather tightness.

16. A closure assembly for a ventilating area consisting of any selected group of unglazed spaces in a window having transversely disposed 25 muntin bars dividing the window into a plurality of spaces some of which are glazed, said closure assembly including a contacting member juxtaposed upon the muntin bars bounding the 30 ventilating area, a fixedly attachable frame and a movably mounted closure including a frame surrounding the glazing, the fixedly attachable frame being juxtaposed upon one side of the 35 contacting member to clamp it against the muntin bars bounding the ventilating area, said contacting member having portions projecting inwardly 40 in a direction parallel to the glazing forming contact seats for the movably mounted closure, the contacting member being provided with a channel opening towards the sides of the muntin bars bounding the ventilating area, and sealing means being disposed in said channel to peripherally seal 45 the fixedly attachable frame to the muntin bars bounding the ventilating area.

17. A closure assembly for a ventilating area consisting of any selected group of unglazed 45 spaces in a window having a plurality of transversely disposed muntin bars dividing the window into a plurality of spaces some of which are glazed, said closure assembly including flanged 50 channel members, a fixedly attachable frame clamping the channel members against the muntin bars bounding the ventilating area, a movably mounted glazed closure frame supported in said 55 fixedly attachable frame, said channel members having flanges extending parallel to the outside faces of the muntin bars so as to project into the ventilating area on at least three sides thereof, and a screen frame disposed in said frames in en-

gagement with the flanges of the contacting members.

18. A closure assembly for use with any selected group of spaces left vacant in a window having a plurality of horizontal and vertical muntin bars dividing the window into a plurality of spaces, the horizontally disposed bar extending along the bottom of the spaces left vacant being provided with an upwardly projecting flange, said closure assembly including a sill and a movably mounted closure adapted to contact the sill, said sill being provided with a downwardly directed channel portion adapted to be positioned on the upwardly projecting flange of the horizontally disposed muntin bar extending across the bottom 15 of the vacant spaces, said sill being provided with a notch straddling the vertically disposed muntin bar, and sealing material for sealing the juncture between said downwardly directed channel and the upwardly directed flange. 20

19. A closure assembly for use with any selected group of spaces left vacant in a window having a plurality of horizontal and vertical muntin bars dividing the window into a plurality of vacant spaces forming a ventilating area, the horizontally disposed bar extending along the bottom of the ventilating area being provided with an upwardly projecting flange, said closure assembly including a fixed frame having a sill and a movably mounted closure adapted to contact the sill, 30 said sill being notched for the vertical muntin bars extending across the ventilating area, the underside of the sill being provided with a channel portion directed downwardly and seated upon the upwardly projecting flange extending across 35 the bottom of the ventilating area, sealing means for sealing the juncture between the closure frame and the muntin bars bounding the vacant spaces, and means for clamping the closure frame to the muntin bars. 40

20. In a window assembly including a plurality of transversely arranged muntin bars dividing the window into a plurality of spaces, some of which are glazed leaving any area selectable after erection for a ventilating area, the combination 45 including a closure unit assembly removably attached to the muntin bars in the field to optionally close said selected area, said closure unit having an open position and a closed position, said closure unit including a frame juxtaposed upon the muntin bars bounding at least three sides of said selected area, sealing means held between three sides of the frame and the bars bounding the selected area for sealing the frame along said sides, means for sealing the fourth side, and means for securing said frame in position to close the selected area when the closure unit is in closed position. 50 55
